UNITED STATES PATENT OFFICE

DENNIS A. CASEY AND ANTHONY J. LIUZZA, OF NEW ORLEANS, LOUISIANA

WALL STRUCTURE

Application filed September 12, 1928. Serial No. 305,549.

This invention relates to improvements in building blocks and tiles for use in constructing building walls and has as one of its objects to provide a novel construction and arrangement of building blocks or tiles which will provide for thorough ventilation of the walls constructed by the use thereof thus preventing the seepage of moisture into the building and greatly prolonging the life of the structure.

Another object of the invention is to provide a building block made up of assembled sections which are brought together at the time of erecting the building wall and to so form the sections that a very substantial structure will be produced and one which will present a very attractive appearance.

Another object of the invention is to provide a building block comprising inner and outer wall sections so formed that the same will be relatively light in weight and yet possess maximum strength so that the component parts of a building wall may be assembled, by the use of the tile or block sections embodying the invention, with less labor than where solid blocks are required to be handled.

Another object of the invention is to provide a building block consisting of assembled wall members so constructed and formed that the component members may be readily assembled and, when assembled, will present a highly attractive wall surface and one which will be substantial and durable.

Another object of the invention is to provide a building block made up of a number of assembled sections or walls and in which the component parts will be so formed and constructed as to permit of a wide range of choice in the arrangement of the sections to construct the blocks and in the arrangement of the blocks in the wall structure.

While the accompanying drawings and the description which is to follow, constitute a disclosure of the preferred embodiment of the invention, it will be understood that various changes may be made within the scope of what is claimed.

In the accompanying drawing:

Figure 1 is a fragmentary perspective

view of one corner of a building structure illustrating the blocks embodying the invention and the manner in which the same may be arranged in erecting the wall structure.

Figure 2 is a perspective view of one of the wall sections of one of the straight wall blocks, looking at the side thereof which will be exposed when the section is assembled with the other sections of the block.

Figure 3 is a view similar to Figure 2 looking at the other side of the section.

Figure 4 is a vertical transverse sectional view through the block section shown in Figures 2 and 3.

Figure 5 is a view similar to Figure 2 illustrating a block which is employed at the corners of a wall structure made up of the blocks embodying the invention or where half blocks are required to be laid.

Figure 6 is a view similar to Figure 3 looking at the other side of the block shown in Figure 5.

Figure 7 is a perspective view of one of the end sections of a block constructed in accordance with the invention.

Figure 8 is a vertical transverse sectional view through the block shown in Figure 7.

The blocks which go to make up a wall structure, in accordance with the principles of the invention, consist of a number of wall sections which are assembled with one another and certain of which sections are common to relatively adjacent or companion blocks, and as the arrangement of these sections varies slightly in the construction of the straight wall portions and the corner wall portions of the building structure, the sections which go to make up the blocks will first be described in detail and the manner in which these sections may be assembled in the erection of a building wall will then be described.

One of the sections which is employed both in the straight wall parts of the structure as well as the corners, is best illustrated in Figures 2, 3 and 4 of the drawing and a indicated by the numeral 1 and this section, as well as the other sections to be hereinafter described, may be made of cement or clay and molded in the usual manner. This sec-

tion 1 has a finished face 2, the section being of oblong rectangular form, and an inner face 3 which is formed with a recess 4 likewise of oblong rectangular form and of dimensions sufficiently less than the corresponding dimensions of the face of the section as a whole, to provide a marginal portion 5 which is of sufficient thickness to insure of the section having the desired strength, the 10 formation of the recess 4 however reducing the weight of the section as a whole. In this block section the edges are not exposed and they are therefore left unfinished but, as stated, the face 2 of the section is finished 15 and any desired ornamental finishing may be provided in the molding operation, as desired.

Figures 5 and 6 illustrate clearly another form of section which is of rectangular form 20 but preferably square as distinguished from oblong and this section, which is indicated by the numeral 6, has an outer face 7 which is preferably finished in the same manner as the face 2 of the section 1, the opposite 25 face of the section, indicated by the numeral 8, and constituting the inner face thereof, being formed with a recess 9 corresponding to the recess 4 of the section 1. In this form of section, one edge, as well as the face 7, 30 is preferably finished so that it may match with the finish of the face 2 of a section 1 adjacent which it is arranged and as the section is of symmetrical form, it will be understood that it may readily be arranged 35 so that its face 8 will be presented inwardly and its finished edge, which is indicated by the numeral 10, may be presented outwardly.

Figures 7 and 8 illustrate another form of block section which is indicated in general by the numeral 11 and which is of rectangular form and preferably square and one edge of this section as for example the edge which is indicated by the numeral 12, is preferably finished as in the manner 40 of the faces 2 and 7 of the sections 1 and 6 respectively, this section being formed with a relatively large circular opening 13 equidistantly spaced with respect to the edges of the section and providing for the passage 45 of air currents past the section when the section is assembled with the other sections in the construction of a building wall.

Referring now to Figure 1 of the drawing which illustrates the blocks built up of the 50 sections above described, it will be observed that the straight part of the wall is erected by assembling two of the sections 1 with their recessed faces 3 presented inwardly and two of the sections 11 which are disposed at their vertical margins against the end edges of the sections 1, these assembled sections being united by a mortar bond 14 applied between their abutting marginal portions as shown clearly in Figure 1. Likewise as shown in the said figure, the assem-

bled sections 1 are arranged in staggered relation in successive rows of the assembled sections in the same manner that bricks or building blocks are arranged in any ordinary wall structure. Where a corner is 70 being erected, the sections 6 are brought into use and, as illustrated in Figure 1, each of these sections is disposed with its inner or recessed face 8 in facial contact with that side of the section 11 which is at the end of 75 the sections 1 of the block assemblage of which it forms a part and which end is the end presented at the corner of the structure as a whole, so that the face 7 of the section 6 will be presented outwardly and as will 80 also the edge 10 thereof and this edge will, being finished, present the same appearance as the edge 12 of the section 11 against which it is disposed and also the same appearance as the face 2 of the section 1. In the assembled relation of all of the sections, it will be evident that the finished faces or edges thereof will be flush at the faces of the wall structure as a whole and of course all assembled sections are united by a mortar bond 85 such as the bond 14 above referred to.

It will be evident from the foregoing description of the invention that the block sections above described may be readily assembled in the erection of a wall structure and that, due to the provision of the openings 13 in the sections 11, a free circulation of air 90 between the sections 1 and throughout the entire wall is provided for thus insuring against the seepage of moisture through the 100 wall and likewise prolonging the life of the structure.

Having thus described the invention, what we claim is:

1. In a wall structure of the character described, a pair of elongated sections having finished outer faces, an inner end section fitting across adjacent ends of the elongated sections, all sections being connected by a mortar bond, the inner end section having a finished outer edge, and an outer short end section having a finished outer face and edge and fitting upon and being bonded to the inner end section, thereby strengthening the end construction of the wall structure, as and 105 for the purposes set forth.

2. In a corner wall structure of the character described, a pair of elongated spaced apart sections, a short inner end section extending across adjacent ends of the elongated sections and having its ends terminating evenly with the outer surfaces of the elongated sections, another pair of elongated spaced apart sections extending transversely to the first elongated sections and partly thereacross with one elongated section of the latter pair bearing upon the inner end section, a second inner end section extending across the ends of the last-mentioned elongated sections and having one edge engaging 110 115 120 125 130

the side of the first inner end section, and an outer end section fitting upon the last inner end section and having its outer face in alignment with the outer face of the outer section of the first elongated sections, all sections being bonded together by mortar, whereby the assemblage forms a reinforced corner, as and for the purposes set forth.

5 In testimony whereof we affix our signatures.

10 DENNIS A. CASEY.
ANTHONY J. LIUZZA.
